(74) Attorney, Agent, or Firm — Banner & Witcoff, Ltd.

(57) CLAIM

The ornamental design for a suitcase, as shown and described.

DESCRIPTION

FIG. 1 is a perspective front view of a suitcase showing our new design;

FIG. 2 is a perspective rear view thereof;

FIG. 3 is a rear view thereof;

FIG. 4 is a right side view thereof;

FIG. 5 is a top view thereof; and,

FIG. 6 is a bottom view thereof.

The broken lines show a portion of the suitcase which form no part of the claimed design.

1 Claim, 6 Drawing Sheets(56)
